UNITED STATES PATENT OFFICE.

EMIL JAGENBERG, OF DUSSELDORF, GERMANY.

MACHINE FOR PASTING SHEETS ON BOXES AND PARCELS.

1,235,690.

Specification of Letters Patent. Patented Aug. 7, 1917.

Application filed December 10, 1915. Serial No. 66,176.

To all whom it may concern:

Be it known that I, EMIL JAGENBERG, a subject of the German Emperor, and resident of 107 Himmelgeisterstrasse, Dusseldorf, Germany, manufacturer, have invented certain new and useful Improvements in Machines for Pasting Sheets on Boxes and Parcels, of which the following is a statement.

10 The present invention relates to a machine for pasting sheets on boxes and parcels.

The essential feature of the new machine consists in the arrangement of the sheet applying attachment beside a shaft, in which 15 the boxes are conveyed from one conveying means to another. By this arrangement it is rendered possible, that the sheets are pasted on the boxes, while these are being transferred from the supplying conveyer 20 to a second conveyer.

The invention further relates to other new constructional features, which are disclosed in a detailed manner in the hereinafter following description and specified in the 25 claims.

In the accompanying drawings a constructional form of the labeling machine has been shown by way of exemplification.

Figure 1 is a side elevation,

30 Fig. 2 is a plan,

Fig. 3 is a vertical section on the line A—B in Fig. 2;

Figs. 4 and 5 are sections on the line C—D in Fig. 2 in two different operative 35 positions.

Fig. 6 is a section on the line E—F.

Figs. 7-11 show the sheet in various positions during the pasting process.

To the bedplate 1 of the machine are secured four standard bearings 2, in which 40 rollers 3, 4, 5 and 6 are journaled. These rollers form two superimposed labeling arrangements, as have been substantially described in the United States Patent 860,148 dated July 16, 1907, and the United States Patent No. 1,143,968 dated June 22, 1915. The drive is effected from the shaft 7 by means of the shafts 8 and the bevel gears 9. As all rollers are provided with intermeshing 45 gears 10 they roll on each other, the rollers 3, 4 conveying the glue from the glue vessel 11 to the segments of the rollers 5 which draw the sheets from the piles 12 and transfer them to the segments of the rollers 6, on 50 which the sheets are held by means of the grippers 14. The piles of sheets stand on

slides 15, which may be reciprocated in guides 16 on the standards 2 by means of levers 18. These levers ride with rollers 19 on cam disks 20 fitted to shaft 5.

In the bedplate 1 a belt pulley 21 is journaled, which is intermittently driven by means of the ratchet gear 22 and the rod gear 23 from a cam, fitted to shaft 7. Over pulley 21 is laid a conveyer belt 24, which feeds the boxes or parcels 25 from any suitable point to the machine. Behind the pulley two plates 26 are fitted to vertically displaceable rods 27 which are adapted to be simultaneously raised and lowered by the lever 28 of a cam 29 fitted to shaft 7. The boxes are successively pushed from the conveyer belt 24 onto these plates 26, which thereupon raise such box between the segment rollers 6. During this operation the 75 segments roll over the surfaces of the box, and paste the sheet in known manner to the latter (Fig. 7). Over these segment rollers rubber pads 30 are secured to levers 31, which are fitted to shafts 32, to which are 80 fitted levers 33 which are rotated by means of cams 34 fitted to the shafts of the rollers 6, so that the rubber pads are pressed against the boxes and thereby press down the sheet which has been pasted onto the same. Between the said rubber pads and the sheets 85 pasted on project thin rods 35 fitted to a rail 36, in order to lift these sheets from the segments and to prevent their curling in consequence of the glue applied to them. When the pads press against the sheet, these thin rods or wires 35 enter into recesses 37 in the said rubber pads.

At the same level with the raised plates 26 two parallel rails 38 are provided beside 95 the latter, beneath which a long slide 39 rests in guides 40, which are fitted to rods 41 vertically displaceable in the bedplate of the machine. These rods 41 are adapted to be simultaneously raised and lowered by means 100 of bell cranks 42 and rods 43 operated by a cam fitted to shaft 7. The slide 39 is coupled by a rod 44 to the lever 45, which is rocked to and fro by means of a rod 46 attached to it and a cam fitted to shaft 7, so 105 that the slide is reciprocated. The movement of the slide and that of the rods 41 are so timed that the slide, when in raised position, will be moved away from the plates 26, then lowered and will, in such lowered position, return and thereupon rise again. To 110 the slide are fitted ears 47, which, when the

slide is raised, project upward between the rails 38, when, however, the slide is lowered, remain below the rails. When the slide is moved toward the plates 26, the first ear 47, 5 on the slide rising, engages behind the box lying on the plates 26 and transfers the same to the rails 38 when the slide moves. By such means the articles are transferred to the rails 38 and thereupon intermittently 10 advanced on the same at fixed intervals (Fig. 2).

To the bedplate of the machine are fitted two brackets 48 which carry guides 49 for slides 50. These slides have pins 51 over 15 which engage the bifurcated ends 52 of levers 53, to the shafts 54 of which levers 55 are fitted, which are rocked by means of rods 56 from cam disks 57, so that the slides 50 are reciprocated. The slides have 20 cross beams 58 to which arms 59 are fitted, which have bifurcated heads 60 at their ends, in which arms 61 are pivotally journaled. The inwardly projecting ends of 25 these arms 61 are provided with recesses 62, into which disks 63 project, which are fitted to the ends of rods 64. These rods 64 project displaceably through the ends of the cross beams 58 and through slotted arms 65, fitted to the brackets 48. By means of 30 springs 66 around pins 67 and adjustably held by nuts 68 the ends of the said slotted arms 65 are pressed against the rod 64. The two attachments which are opposite to each other and are fitted to the ends of the cross 35 beams turned toward the labeling devices are similar to each other but different from the other two attachments. To each arm 61 of the two first attachments is fitted a rail 69 to which brushes 71 are secured by means 40 of straps 70. The other two attachments, on the contrary, have the rails 69 with straps 70 and brushes 71 fitted only to the arms 61 at the side. Above and below these brushes blades 73 pivoting on shaft 72 45 are provided, which are drawn toward each other by means of springs 74 and which rock simultaneously with the brushes toward the inside or outside respectively. At top and bottom bifurcated heads 75 are fitted to the 50 arms 59 in which arms 112 are journaled, which with their slotted inner ends engage over the disk 63, and have at their outer ends rails 77, to which blades 78 are fitted.

When the articles are pushed onto the 55 rails 38 the edges of the paper sheets projecting at top and bottom abut against curved rails 79, which fold over these edges onto the article and press them thereagainst. At the next advance by means of ears 47 the 60 respective article arrives in front of the brushes 71 and the preceding article in front of the brushes 71 and the blades 73, 78. Now the two slides 50 advance simultaneously. The clamps 65, 66, 67 hold the 65 rods 64, so that the disks 63 move toward

the cross beam and thereby rock the brushes and blades 73, 78 toward the inside and against each other, so that they pass over the edges of the box and fix down the sheet pasted thereon, besides folding over any 70 still projecting parts against the box and fixing such parts thereto. (Fig. 9). The blades 73, 78 therewith bear against the still projecting ears 80 from above and below, so that these ears are sharply folded 75 over. Then the slides 50 recede, the clamps 65—68 again holding the rods 64, and in consequence thereof rocking the brushes and blades 73, 78 toward the outside, so that the parts of the sheets which have been folded over are not torn off again.

For the blades to glide exactly over the ears 80, it is necessary that the box lies quite straight. This is insured by means of two hooks 81, which are fitted to a common shaft 85 82, and are raised and lowered by an arm 83, which bears on a pin 84 in a vertically displaceable rod 85, which itself is raised and lowered by means of a lever 86 and a cam disk 87.

On the bedplate 1 are fitted vertical columns 88, on which slides 89 are disposed, which carry rails 90, on which bifurcated heads 91 are carried and in these arms 92 are arranged. The arms are coupled to rails 93 to which by means of straps 94 brushes 95 are secured, and the other ends of said arms are provided with notches 96, into which engage disks 97, which are fitted to rods 98. These rods project through slotted 100 arms 99 fitted to the columns 88, the ends of which arms are pressed against each other and against the rods 98 by means of springs 100. On the ends of rods 98 which are beside the disks 97 are secured rubber 105 pads 101. About the middle of each column 88 is pivoted a double-armed lever 102, the ends of which are coupled by rods 103 to the slides 89 on said columns. To the lever 102 are furthermore linked rods 104, to 110 which bell cranks 105 are coupled, which by means of rods 106 are operated from cam disks on shaft 7. When the rods 104 are raised, the slides 89 simultaneously move toward each other. The rods 98 are, however, held back by their friction, so that the brushes 95 rock against each other and therefore pass along over the edges of the box and fold over the ears 80, fixing them down (Fig. 11). When the slides 115 thereupon recede the clamps 99, 100 will again hold the rods 98, so that the brushes are rocked toward outside and are lifted from the box. The further advance of the articles by means of slide 39 then transfers the 120 articles to a conveyer path or some other device.

It is obvious that many modifications regarding the construction of the hereinbefore described machine may be made with 125

out, however, departing from the essence and spirit of my invention.

What I claim is:

1. Machine for pasting sheets on boxes and parcels consisting of a conveyer belt for the boxes to be pasted, means for lifting the boxes supplied, labeling devices for pasting the sheets to the boxes during such lifting operation, a conveying means for intermittently transporting the pasted boxes, means for folding over the projecting parts of the sheet, means for sharply folding the ears of the sheet, and means for folding over and pressing down the said ears.
- 15 2. Machine for pasting sheets on boxes and parcels, consisting of a conveying means, a labeling device, a second conveying means, brushes for folding over and rubbing down the projecting parts of the sheet,

means for moving the said brushes forward and backward, means for pressing on the brushes during their advance and for lifting them off during their return, reciprocating blades for plaiting the folded over sheets, means for pressing on the said blades during their advance and lifting them off during their return, means for straightening out the boxes, brushes for folding over and pressing down the ears of the sheets, and means for automatically pressing on and lifting off said brushes.

In testimony whereof I have hereunto set my signature in the presence of two subscribing witnesses.

EMIL JAGENBERG. [L.S.]
